UNITED STATES PATENT OFFICE.

FRANK F. GERL, OF MILWAUKEE, WISCONSIN.

DESIGN FOR A GUITAR.

Application filed July 3, 1922. Serial No. 2,941. Term of patent 7 years.

To all whom it may concern:

Be it known that I, FRANK F. GERL, a citizen of the United States, residing at Milwaukee, in the county of Milwaukee and State of Wisconsin, have invented a new, original, and ornamental Design for a Guitar, of which the following is a specification, reference being had to the accompanying drawing, forming part thereof.

I claim:

The ornamental design for a guitar as shown.

FRANK F. GERL.
